UNITED STATES PATENT OFFICE.

WALTER C. TURPEL, OF NEW ORLEANS, LOUISIANA.

HEEL FOR BOOTS AND SHOES.

No. 884,780.

Specification of Letters Patent. Patented April 14, 1908.

Application filed September 21, 1907. Serial No. 393,954.

To all whom it may concern:

Be it known that I, WALTER C. TURPEL, a citizen of the United States, residing at New Orleans, in the parish of Orleans and State of Louisiana, have invented new and useful Improvements in Heels for Boots and Shoes, of which the following is a specification.

This invention relates to heels for boots and shoes; and it has for its objects to provide a heel having a movably supported top lift different portions of which will be successively exposed to wear, thereby increasing the life of the heel and maintaining the latter straight and level with little or no tendency to run down at the side owing to unequal wear upon the different parts.

Another object is to construct a heel of the character described including a rubber or other resilient portion and an air cushion which will take up the jar shock caused by placing the heel on the ground, in walking, thus rendering the use of the shoe equipped with the improved heel easy and comfortable for the wearer.

Further objects are to simplify and improve the construction of this class of devices.

With these and other ends in view which will readily appear as the nature of the invention is better understood, the same consists in the improved construction and novel arrangement and combination of parts which will be hereinafter fully described and particularly pointed out in the claims.

In the accompanying drawings has been illustrated a simple and preferred form of the invention; it being, however, understood that no limitation is necessarily made to the precise structural details therein exhibited, but that changes, alterations and modifications within the scope of the invention may be resorted to when desired.

In the drawing, Figure 1 is a side elevation of a shoe equipped with the heel constructed in accordance with the invention, the heel being shown in vertical section. Fig. 2 is a plan view of the underside of the heel. Fig. 3 is a plan view of the rotary top lift. Fig. 4 is a detail plan view of the metallic washer connected with and supporting the rotary top lift.

Corresponding parts in the several figures are denoted by like characters of reference.

In its preferred form, the improved heel includes a cushion 1 of rubber or other suit-

able resilient material, the same being secured upon the heel foundation which preferably includes a plurality of lifts 2—2 secured in the usual manner upon the shoe. The cushion 1 which is of a size and shape to fit upon the heel foundation is provided with a recess 3 constituting an air chamber, said recess being preferably of circular shape; and adjacent to said recess, and preferably concentric therewith, is formed another and relatively shallow recess 4 constituting a seat for the circular top lift 5 which is preferably made of leather, and provided with a central aperture 6 for the accommodation of the head of the screw or fastening member 7 which extends through the cushion 1 and into the foundation formed by the lifts 2—2. Securely attached upon the underside of the top lift 5 is a washer consisting of a plate 8 of steel or other suitable material having an aperture 9 for the passage of the shank of a screw or fastening member, the head of which engages the outer side of the washer 8, and serves to secure the washer and the top lift in position, revolvable.

In practice, the cushion 1 serves the purpose of the ordinary rubber heel, but its efficiency is greatly increased by the presence of the air chamber 3 which is closed by the rotary lift composed of the leather disk 5 and the washer 8; it being obvious that when the foot is set upon the ground, in walking, the air contained in the recess 3 will be compressed and form a cushion whereby the jarring will be prevented and walking rendered easy and comfortable. Every time the heel is set upon the ground, there will be a tendency to displace the top lift which will result in the partial rotation of said top lift so that, at each step, a different portion of said top lift will be exposed to wear; the natural consequence of this is, that the wear will be equally distributed, and there will be little tendency for the heel to become run down at the side; the heel will thus not only be retained in a neatly appearing and level condition, but its life will be greatly increased since all portions of the top lift will be gradually and evenly worn. The head of the fastening member 7 is countersunk in the top lift, and no nail heads or other metallic portions will be exposed; hence there will be little tendency to slipping, any tendency in this direction being also counteracted by the presence of the rubber cushion.

110

The construction is simple and inexpensive, and the device is thoroughly efficient for the purposes for which it is provided.

Having thus fully described the invention, what is claimed as new is:—

1. In a heel, a resilient or compressible member having a recess constituting an air chamber, and a top lift supported for rotation adjacent to said air chamber and constituting a closure therefor.

2. In a heel, a resilient or compressible member having a recess constituting an air chamber, and a shallower recess adjacent to and concentric therewith, in combination with a top lift seated revolvably in the shallower recess and constituting a closure for the air chamber.

3. A heel comprising a foundation, a rubber cushion secured upon the foundation and having a recess constituting an air chamber, a top lift supported for rotation adjacent to the air chamber and constituting a closure therefor and a fastening member for said top

lift having a head countersunk therein and a shank extending through the cushion member into the foundation of the heel. 25

4. In a heel, a foundation, a cushion secured upon the foundation and having a recess constituting an air chamber, and a shallower recess concentric therewith, a leather top lift seated in the shallower recess and having a central aperture, a metal washer secured upon the underside of the top lift, and a headed fastening member extending through the washer, the air chamber and the cushion into the foundation of the heel, the head of said fastening member being accommodated in the central aperture of the top lift. 30 35

In testimony whereof I affix my signature 40 in presence of two witnesses.

WALTER C. TURPEL.
